Des. 188,962
Patented Oct. 4, 1960

188,962

VENTILATING FAN HOUSING

Henry Zeiler, Rte. 1, Box 30, Windsor, Colo.

Filed May 2, 1960, Ser. No. 60,399

Term of patent 14 years

(Cl. D62—4)

Fig. 1 is a front perspective view of a ventilating fan housing showing my new design;

Fig. 2 is a side elevational view thereof; and

Fig. 3 is a top plan view thereof.

The sides not shown are substantially the same as the sides shown.

I claim:

The ornamental design for a ventilating fan housing, as shown and described.
